UNITED STATES PATENT OFFICE.

HENRY G. VOIGHT, OF NEW BRITAIN, CONNECTICUT, ASSIGNOR TO THE RUSSELL & ERWIN MANUFACTURING COMPANY, OF SAME PLACE.

CUPBOARD-LATCH.

SPECIFICATION forming part of Letters Patent No. 634,565, dated October 10, 1899.

Application filed August 1, 1898. Serial No. 687,399. (No model.)

To all whom it may concern:

Be it known that I, HENRY G. VOIGHT, a citizen of the United States, residing at New Britain, in the county of Hartford and State of Connecticut, have invented certain new and useful Improvements in Cupboard-Latches, of which the following is a specification.

My invention relates to improvements in cupboard-latches; and the main object of my improvement is to inclose the tail end of the latch without increasing the length of the case.

In the accompanying drawings, Figure 1 is a front elevation of my latch. Fig. 2 is a rear elevation. Fig. 3 is a side elevation showing the face-plate and beveled end of the latch-bolt. Fig. 4 is a sectional view on the line xx of Fig. 1. Fig. 5 is a sectional view on the line yy of Fig. 1. Fig. 6 is a side elevation of the rear plate of my latch.

The case A is formed of sheet metal, the face-plate 7 of which is provided with a hole for the beveled end of the latch-bolt to slide in. This hole is made to conform to the shape of the latch-bolt at the head end, which shape will be described in connection with the latch-bolt.

Above and below the body or middle portion of the case A, I form the wings 8, the edges of the metal forming said wings being turned at right angles to their plate portion, as at 9, in order to elevate said plate portion a little from the back face of the latch. Said wings may have any ordinary screw-holes formed in them, but I prefer to swage the countersink of the screw-holes in the form of integral eyelets 10, as shown best in Fig. 5.

The sides 11 of the latch-bolt at its beveled or head end 12 are inclined toward each other as they extend from front to rear, as shown in Figs. 2 and 3, and the hole in the face-plate

7 is of a corresponding shape, whereby the said end 12 is supported within said face-plate against moving to the rear during the entire inward stroke of the latch-bolt. The said latch-bolt on the inside of the case is provided with an ordinary yoke 13 for the cams 14 of the knob 15 to act upon in the ordinary manner and also with a central stem 16 to guide the rear end of the latch, and about which stem I place the spiral spring 17. The rear end of this stem extends to the rear about

the same distance as the ends of the yoke and is thus shorter than the stem in ordinary cupboard-turns. I support this stem by means of a lug 18 on the partial rear plate 19, said lug, as shown best in Fig. 4, standing in a position some distance from the end plate 20 of the case, so that the stem may have room to make its full stroke without perforating said end plate, thereby avoiding the projection of the stem from the case, which projection is objectionable in the ordinary cupboard-latch. At the same time the case is not materially longer than is necessary for the yoke and cams to operate in. The cams 65 in acting on the yoke to draw in the latch-bolt move along close to the inner face of the case A and over the end of the lug 18, which lug must be short enough not to interfere with the operation of said cams. This partial rear 70 plate at its ends enters the recesses in the rear side of the wings, and I prefer to secure it in place by extending the eyelets 10 through holes in said plate and clenching them over the same, as best shown in Fig. 5; but the 75 other parts of my invention would be the same if this rear plate were secured in place in some other way. The partial rear plate extends only over a portion of the rear side of the plate—that is to say, it does not extend in the rear of the head of the latch-bolt, so as to support that end. I am enabled to use this partial rear plate by having the sides 11 of the latch-bolt inclined, as shown, while the stem end of the latch-bolt is supported 80 by the lug on said partial rear plate, and thus I make a cheap latch in which the stem never projects through the end plate of the case, and the latch-case is substantially no longer than is necessary for the proper operation of the cams and yoke.

I am aware that a prior patent shows a cupboard-latch with its bolt having inclined sides on its head end and supported in a face-plate having a correspondingly-shaped hole, and I hereby disclaim the same.

It is apparent that some changes from the specific construction herein disclosed may be made, and therefore I do not wish to be understood as limiting myself to the precise 100 form of construction shown and described, but desire the liberty to make such changes

in working my invention as may fairly come within the spirit and scope of the same.

I claim as my invention—

1. In a cupboard-latch, the combination of the box-like case having a face-plate with latch-bolt opening that tapers toward the rear and having above and below the body portion of the said case the wings 8 with turned edges 9 forming recesses in the back of the said wings, with a latch-bolt having its head end fitted to the said tapering hole in the face-plate and supported by the said face-plate, and the partial rear plate having the perforated lug for supporting the stem of the latch-bolt and having its ends resting within the recesses of the wings 8 and secured to the rear side of said wings inside of the edges 9, substantially as described.

2. In a cupboard-latch, the combination of the latch-bolt having the yoke and stem, with the box-like case, the partial rear plate having the lug 18 on the inside of the case for supporting the stem of the latch-bolt and with a clear space between the front end of said lug and the rear side of the front plate 25 of said case, and a cam mounted on the inside of the said front plate of the case adjacent to the lug and arranged to pass through the space between the front end of said lug and the rear side of the said front plate for acting on the yoke of the latch-bolt, substantially as described.

HENRY G. VOIGHT.
